Primary Examiner — Cynthia M Chin

(74) Attorney, Agent, or Firm — Michael J. Feigin, Esq.;
Feigin and Fridman(57) **CLAIM**

The ornamental design for a toy building block, as shown and described.

DESCRIPTION

FIG. 1 shows a top and side perspective view of the toy building block.

FIG. 2 shows a bottom and side perspective view thereof.

FIG. 3 shows first elevation view thereof, the opposite site being a mirror image thereof.

FIG. 4 shows a second elevation view thereof, the opposite site being a mirror image thereof.

FIG. 5 shows a top plan view thereof.

FIG. 6 shows a bottom plan view thereof; and,

FIG. 7 shows the toy building block connecting a plurality of additional toy building blocks, the dotted lines being unclaimed subject matter shown for illustrative purposes only.

The broken lines shown are included for the purpose of illustrating portions of the article which form no part of the claimed design.

The broken away symbols in the drawings indicate the appearance of any portion of the article between the break lines forms no part of the claimed design.
